UNITED STATES PATENT OFFICE.

LAWRENCE M. WOOD, OF FAIRFIELD, CONNECTICUT.

DESIGN FOR AN AUTOMOBILE-LAMP.

48,698.

Specification for Design.

Patented Mar. 7, 1916.

Application filed November 30, 1914. Serial No. 874,952. Term of patent 3½ years.

To all whom it may concern:

Be it known that I, LAWRENCE M. Wood, a citizen of the United States, residing at Fairfield, county of Fairfield, Connecticut, have invented a new, original, and ornamental Design for an Automobile-Lamp, of which the following is a specification, reference being had to the accompanying drawing, forming part thereof.

The figure is a perspective view of an automobile lamp, showing my new design.

I claim:

The ornamental design for an automobile lamp, as shown.

LAWRENCE M. WOOD.
